POTHEAD DEVICE

Louis H. Thullen, Chicago, Ill., assignor to G. &
W. Electric Specialty Company, Chicago, Ill.,
a corporation of Illinois

Application November 14, 1929, Serial No. 407,074
Renewed October 22, 1934

11 Claims. (Cl. 173—353)

This invention relates to electrical conductors in general, and more particularly to pothead devices such as are used for connecting electrical cables with overhead conductors.

5 Pothead devices usually include a tubular insulation member for receiving an electrical cable. This insulation member is provided with an upper or outlet end in the form of a metallic contact element adapted to be contacted by an overhead conductor. This contact element is electrically attached to the end of the cable within the insulation member and the inlet end of the insulation member is so connected and attached to the cable as to support the same through the 10 intermediary of its sheath. The cable is adapted to expand and contract longitudinally depending largely upon the amount of current passing therethrough. In order to take the strain off of the insulation member and prevent cracking thereof, 15 usually near the top, as the cable expands and contracts, it is highly desirable to provide some means for yieldably connecting the upper end of the cable to the insulation member, and it is accordingly the primary object of this invention to provide such a connection.

20 Another object of this invention is to provide such a connection and associated parts of a pothead, which may be economically manufactured, which will be rugged of operation and convenient of assembly, inspection, renewal or repair.

25 Other and further objects of this invention will be apparent as the same becomes better understood from an examination of the specification and claims in connection with the accompanying drawing, wherein—

30 Fig. 1 is a fragmentary elevation of a pothead embodying this invention;

Fig. 2 is a fragmentary vertical section of the same; and

Fig. 3 is an enlarged horizontal section taken at the line 3—3 of Fig. 1.

35 Referring to the drawing more particularly, reference character 4 designates a tubular insulation member provided with an opening 5 at its upper end and closed at its lower end by a suitable closure or housing 6. This closure or housing 6, so far as this invention is concerned, may be of standard form permitting the entrance of a cable 7 into the lower end of the member 4 and providing for the support of said cable through the intermediary of the sheath (not shown) in said member 4, whereby oil or other compound therein may enter the sheath and surround the wrapping of the cable to keep such wrapping in 40 efficient condition and whereby the upper end of

the cable may be connected to a suitable contact or terminal member generally designated by the reference character 8 and which will be more particularly described hereinafter. Although the closure or housing 6 providing for the support of the cable in the inlet of the pothead may be of standard form, it is preferably as illustrated and described in the co-pending application of George P. Edmonds for Pothead devices, filed August 13, 1929, bearing Serial No. 385,641.

45 The upper end of the cable 7 is in the form of a male plug 9, which fits in a suitable socket in the lower end of an extension 11. This extension member acts to electrically connect the end of the cable to a combined cover and contact member 12, said extension being provided with a threaded upper portion 13 which is threaded to said cover.

50 The combined cover and contact member, together with the extension 11 forming the terminal member 8, are connected to the upper end of the insulation member 4 through the intermediary of a cylindrical member 14 which is in the form of an expandable and contractible metallic bellows and which surrounds the extension 11 and is connected thereto at its upper end, its lower end being connected to the insulation member 4.

55 The upper end of the bellows 14 has its brim sweated to the outer periphery of a circular member 15, which is clamped between a nut 16 on the portion 13 and a circular shoulder 17 on the extension 11, a washer 18 being disposed between said nut and shoulder to form a non-leakable joint therebetween.

60 The lower end of the bellows 14 has its brim sweated to the inner periphery of a cylindrical member 19, which is provided with a circular flange 21 engaging an inner shoulder 22 in the member 4 at the bottom of the opening 5. This member 19 is provided with a nut 23 for compressing the flange 21 against the shoulder 22 through the intermediary of a washer 24 for forming a non-leakable joint and for supporting said member in the opening 5, a washer 25 being 65 also provided between the nut and the upper end of the member 4.

65 In order to prevent rotational movement of the extension 11 and possible working loose thereof in consequence of such movement, the same is 70 provided with angularly spaced laterally extending integral ears 26, which are adapted to engage with inwardly extending integral ears 27 formed in the inner periphery of the member 19.

75 In order to facilitate the renewal of oil within 55

the pothead the member 15 is tapped and provided with threaded plugs 28 which may be removed to admit oil through openings 29 to the interior of the pothead.

- 5 The housing or closure 6 is attached through the intermediary of bolts 31 to ring 32 cemented to the lower end of the member 4. A bracket 33 is bolted to the lower end of the housing 6 and this bracket is provided with a suitable clamp 10 (not shown) for supporting the pothead.

It will be apparent that whenever the cable 7 longitudinally expands or contracts, the bellows 29 will permit relative movement of the terminal or contact element 8 with respect to the insulation member 4 without danger of breaking the connection between said terminal member and insulation member. It is also to be noted that the connection between the terminal or contact member 8 and the insulation member 4 offered by 15 the bellows 14 and the annular members 15 and 19 by means of which the bellows is attached to the members 8 and 4, respectively, is a non-leakable connection.

The other advantages of the aforescribed 25 construction will be apparent without further description.

I am aware that many changes may be made without departing from the principles of this invention and I therefore do not wish to be limited 30 to the details shown or described.

What I claim is:

1. In a device of the character described, the combination of a cable and a tubular insulator member adapted to enclose the upper end of said cable, a cylindrical expandable member adapted to be connected at one end to the insulator member and at the other end to the cable, and means for connecting the ends of said expandable member to the parts to which they are adapted to be 35 connected, said means including a shoulder on the insulator member, an annular member provided with an annular flange, a washer between the said shoulder and flange, and a second member movable relative to the flange for clamping 40 said washer to form a non-leakable connection between one end of said expandable member and the part to which it is connected.

2. In a device of the character described, the combination of a cable and a tubular insulator 50 member adapted to enclose the upper end of said cable, a cylindrical expandable member arranged to permit relative longitudinal movement between the end of said cable and said insulator member; a cable terminal, a circular member attached to the upper end of said cylindrical expandable member, a cylindrical flanged member attached to the lower end of said expandable cylindrical member, means for engaging the said cylindrical flanged member on the insulator, and means for engaging the said circular member to the cable 55 terminal.

3. In a device of the character described, the combination of a cable and an interiorly flanged tubular insulator member adapted to enclose the 60 upper end of said cable, a flanged cylindrical member removably attached to the insulator to engage the said insulator flange, a terminal fitting secured to the upper end of the cable, an expandable cylindrical member associated with the 65 said flanged cylindrical member and the said terminal fitting to permit their relative longitudinal movement; inwardly projecting ears on the flanged cylindrical member and outwardly projecting ears on the terminal fitting, said ears 70 arranged to interlock so as to prevent relative ro-

tational movement but to permit relative longitudinal movement of the cable and the insulator member.

4. In a device of the character described including a cable, a tubular insulator member and an expandable and contractible tubular member in the form of a bellows having means for connecting the said cable and the said insulator, said means comprising a metal fitting rigidly and hermetically secured to the top of the expandable 10 member and screw-threadedly secured to the cable terminal, a second metal fitting in the form of a hollow bolt rigidly and hermetically secured to the bottom of said expandable member and nut means bearing on the top of the insulator member 15 for mechanically securing said fitting to said insulator member.

5. A device of the class described, comprising a tubular insulator having a flange defining an opening at one end thereof, a cable extending 20 into said opening and having a terminal extending through said opening, a connecting unit for flexibly connecting said cable terminal to said insulator and for closing the opening thereof, said unit comprising an expandable and contractible member surrounding said terminal, a sleeve connected to said expandable and contractible member to form a permanent connection therebetween in the assembly under normal conditions and having a flange in abutting relation 25 with the flange of said insulator, and means for holding said flanges in said abutting relation whereby said sleeve is secured to said insulator, and means secured to the other end of said expandable and contractible member to form a permanent connection therebetween in the assembly 30 under normal conditions and secured to said cable terminal to provide a readily detachable connection therebetween in the assembly under normal conditions.

6. A device of the class described, comprising a tubular insulator having a flange defining an opening at one end thereof, a cable extending into 40 said insulator and having a terminal extending through said opening, a connecting unit for flexibly connecting said cable terminal to said insulator and for closing the opening thereof, said unit comprising an expandable and contractible member surrounding said terminal, a sleeve connected to said expandable and contractible member to form a permanent connection therebetween in the assembly under normal 45 conditions and having a flange in abutting relation with the flange of said insulator, a lock nut adjustably mounted on said sleeve and in abutting relation to said insulator to draw said flanges into abutting relation whereby said sleeve is secured to said insulator, washers between said insulator, sleeve and lock nut to provide a fluid tight joint between said sleeve and insulator, and means 50 secured to the other end of said expandable and contractible member to form a permanent connection therebetween in the assembly under normal conditions and secured to said cable terminal to provide a readily detachable connection therebetween in the assembly under normal 55 conditions.

7. A device of the class described, comprising a tubular insulator having a flange defining an opening at one end thereof, a cable extending 60 into said insulator and having a terminal extending through said opening, a connecting unit for flexibly connecting said cable terminal to said insulator and for closing the opening thereof, said unit comprising an expandable and contractible 65 member surrounding said terminal, a sleeve connected to said expandable and contractible member to form a permanent connection therebetween in the assembly under normal conditions and secured to said cable terminal to provide a readily detachable connection therebetween in the assembly under normal 70 conditions.

ble member surrounding said terminal, a sleeve connected to said expandable and contractible member to form a permanent connection therebetween in the assembly under normal conditions 5 and having a flange in abutting relation with the flange of said insulator, means for holding said flanges in said abutting relation whereby said sleeve is secured to said insulator, and a member secured to said expandable and contractible member to form a permanent connection therebetween in the assembly under normal conditions, said member embracing said cable terminal, and means for securing said last-named member to said terminal to provide a readily detachable 10 connection therebetween in the assembly under normal conditions.

8. A device of the class described, comprising a tubular insulator having a flange defining an opening at one end thereof, a cable extending 20 into said insulator and having a terminal extending through said opening, a connecting unit for flexibly connecting said cable terminal to said insulator and for closing the opening thereof, said unit comprising an expandable and contractible member surrounding said terminal, a sleeve connected to said expandable and contractible member to form a permanent connection therebetween in the assembly under normal conditions and having a flange in abutting relation with the 25 flange of said insulator, a lock nut adjustably mounted on said sleeve and in abutting relation to said insulator to draw said flanges into abutting relation whereby said sleeve is secured to said insulator, washers between said insulator, sleeve and lock nut to provide a fluid tight joint 30 between said sleeve and insulator, a member secured to said expandable and contractible member, said member embracing said cable terminal and means for securing said last named member to said terminal to provide a readily detachable connection therebetween in the assembly under 35 normal conditions, and means on said sleeve and said terminal for limiting rotation of said terminal in respect to said insulator but permitting relative movement of translation between said terminal and insulator.

40 9. A device of the class described, comprising a tubular insulator having a flange defining an opening at one end thereof, a cable extending into said insulator and having a terminal extending through said opening, a connecting unit for 40 flexibly connecting said cable terminal to said insulator and for closing the opening thereof, said unit comprising an expandable and contractible member surrounding said terminal, a sleeve connected to said expandable and contractible 45 member to form a permanent connection therebetween in the assembly under normal conditions and having a flange in abutting relation with the flange of said insulator, a lock nut adjustably mounted on said sleeve and in abutting relation 50 to said insulator to draw said flanges into abutting relation whereby said sleeve is secured to said insulator, washers between said insulator, sleeve and lock nut to provide a fluid tight joint 55 between said sleeve and insulator, a member secured to said expandable and contractible member to form a permanent connection therebetween in the assembly under normal conditions, said last named member embracing said cable terminal, and means for securing said last named 60 member to said terminal to provide a readily detachable connection therebetween in the assembly under normal conditions, and a washer disposed between said terminal and said last named member to provide a fluid tight joint therebetween.

5 10. A device of the class described, comprising a tubular insulator having a flange defining an opening at one end thereof, a cable extending into said insulator and having a terminal extending through said opening, a connecting unit 10 for flexibly connecting said cable terminal to said insulator and for closing the opening thereof, said unit comprising an expandable and contractible member surrounding said terminal, a sleeve connected to said expandable and contractible 15 member to form a permanent connection therebetween in the assembly under normal conditions and having a flange in abutting relation with the flange of said insulator, a lock nut adjustably mounted on said sleeve and in abutting relation 20 to said insulator to draw said flanges into abutting relation whereby said sleeve is secured to said insulator, washers between said insulator, sleeve and lock nut to provide a fluid tight joint 25 between said sleeve and insulator, a member secured to said expandable and contractible member, said member embracing said cable terminal and means for securing said last named member to said terminal to provide a readily detachable connection therebetween in the assembly under 30 normal conditions, and means on said sleeve and said terminal for limiting rotation of said terminal in respect to said insulator but permitting relative movement of translation between said terminal and insulator.

35 11. A device of the class described, comprising a tubular insulator having a flange defining an opening at one end thereof, a cable extending into said insulator and having a terminal extending through said opening, a connecting unit for 40 flexibly connecting said cable terminal to said insulator and for closing the opening thereof, said unit comprising an expandable and contractible member surrounding said terminal, a sleeve connected to said expandable and contractible 45 member to form a permanent connection therebetween in the assembly under normal conditions and having a flange in abutting relation with the flange of said insulator, a lock nut adjustably mounted on said sleeve and in abutting relation 50 to said insulator to draw said flanges into abutting relation whereby said sleeve is secured to said insulator, washers between said insulator, sleeve and lock nut to provide a fluid tight joint 55 between said sleeve and insulator, a member secured to said expandable and contractible member to form a permanent connection therebetween in the assembly under normal conditions, said last named member embracing said cable terminal, and means for securing said last named 60 member to said terminal to provide a readily detachable connection therebetween in the assembly under normal conditions, and a washer disposed between said terminal and said last named member to provide a fluid tight joint therebetween.

65 LOUIS H. THULLEN.
